UNITED STATES PATENT OFFICE.

JOHN A. CHAMBERS, OF NEWBURG, MISSOURI.

MAIL-DELIVERY APPARATUS.

1,405,097.

Specification of Letters Patent. Patented Jan. 31, 1922.

Application filed October 7, 1920. Serial No. 415,294.

To all whom it may concern:

Be it known that I, JOHN A. CHAMBERS, a citizen of the United States, residing at Newburg, in the county of Phelps and State 5 of Missouri, have invented a new and useful Mail-Delivering Apparatus, of which the following is a specification.

This invention relates to mail delivery apparatus for use on mail cars whereby 10 sacks of mail can be delivered automatically from a moving train at any desired point and without danger of injury to the sacks, mechanism being provided whereby the sacks, at the time of delivery, are thrown 15 downwardly and rearwardly so as to offset the momentum due to the forward movement of the train, thus insuring the deposit of the sack at points where they will remain practically stationary.

20 A further object is to provide a structure of this character which can be applied readily to a car, can be folded compactly so as to be out of the way when not in use, and which can be easily loaded and shifted 25 to operative position.

With the foregoing and other objects in view, which will appear as the description proceeds, the invention resides in the combination and arrangement of parts and in 30 the details of construction hereinafter described and claimed, it being understood that, within the scope of what is claimed, changes in the precise embodiment of the invention shown can be made without departing 35 from the spirit of the invention.

In the accompanying drawings the preferred form of the invention has been shown.

In said drawings—

40 Figure 1 is a side elevation of a portion of a car having the present improvements combined therewith, the mail delivery apparatus being shown folded out of the way.

45 Figure 2 is a similar view showing the delivery apparatus shifted to operative position, the said apparatus being in section and the trip in the path thereof being shown in elevation.

50 Figure 3 is a view similar to Figure 2 and showing the apparatus in the act of being tripped for delivering mail.

55 Figure 4 is a front elevation of the delivery apparatus showing the parts in the positions illustrated in Figure 2, the section on which Figure 2 is taken being indicated by the line 2—2 in this figure.

Referring to the figures by characters of reference A designates a portion of a mail car having the usual door opening B. Connected to the side of this car adjacent the back edge of the door opening but below the level of said opening are ears 1 carrying a pivot rod 2 on which are mounted ears 3 extending from one end of a frame 4. This frame includes a top bar 5 and a bottom bar 6. A supplemental frame 7 is arranged within the frame 4 and is hingedly connected thereto by a cross rod 8. A tiltable platform 9 is hingedly mounted within the upper portion of the supplemental frame 70 and has a flange 10 at one end. This platform is adapted normally to lie vertically between the sides of the supplemental frame 7 which, in turn, is supported normally in a vertical position between the sides of the main frame 4. Thus it will be seen that all parts of the structure can be folded compactly against the side of the car A and across the lower portion of the door opening B as shown in Figure 1.

80 A guide rod 11 is secured to one face of the frame 7 and is slidably engaged by a loop 12 formed at one end of a crooked crank arm 13. This crank arm extends through the main frame 4 between the bar 6 and the lower end of the supplemental frame 7 and is carried by one end of a rod 14 journaled on one face of the bar 6. A depending crank arm 15 extends from this rod and, when the parts of the apparatus are folded this crank arm 15 extends downwardly below the main frame 4 as shown in Figures 1, 2 and 4.

At those points along the track where mail is to be discharged an upwardly extending bowed tripping rail 16 is located where it will be contacted by the crank arm 15 during the passage of the car with the delivering apparatus set in operative position.

95 An angular holding bracket or tongue 17 is connected to the bottom of the platform 9. When it is desired to use the apparatus the platform 9, while in the position shown in Figure 1 is swung downwardly to a horizontal position so as to rest on the top bar 5 and is then drawn inwardly toward the door opening so as to cause the bracket 17 to engage the bar 5 and fasten the platform in horizontal position. The sacks of mail to be delivered are then piled on the platform after which the entire structure is 105 swung outwardly and rearwardly to bring 110

the frame 4 in position at right angles to the side of the car as in Figures 2 and 4. This outward movement can be limited by a stop 18 secured to the side of the car and 5 in the path of the frame 4. With the parts thus located the crank arm 15 will, during the forward movement of the car, come against and ride over the tripping rail 16. This will cause the rod 14 to rotate and 10 actuate the crooked crank arm 13 which will thrust rearwardly against the supplemental frame 7 at a point below its pivot rod 8 and cause the upper end of said frame to swing rearwardly away from the bar 5. This will, 15 obviously, move the bracket 17 out of engagement with the bar 5 and the platform 9, being thus released, will be overbalanced by the load thereon and caused to tilt and allow the sacks to slide therefrom and onto 20 the ground. The abrupt rearward swinging movement imparted to the frame 7 by the actuation of the crank arm 15 will tend to toss the sacks rearwardly so as to offset the momentum due to the forward movement of 25 the car. Consequently the sacks will remain practically stationary when deposited on the ground.

What is claimed is:—

1. In mail delivery apparatus the combination with a car having a door opening, 30 of a main frame mounted to swing outwardly and rearwardly relative to the opening to position the frame at right angles to the side of the car; a tiltable platform, a 35 connection between the platform and main frame, said platform connection and frame being foldable together for compact storage against the side of the car, cooperating means upon the platform and frame for holding said platform in load supporting 40 position, a tripping element, and means carried by the frame and actuated by said element for automatically releasing the platform and imparting an abrupt rearward and

downward movement thereto relative to the 45 car.

2. The combination with a car and a tripping element adjacent the path thereof, of a structure mounted to swing laterally rearwardly relative to the car, to position the 50 structure at right angles to the side of the car, said structure being movable with the car, a tiltable platform movable with said structure, a connection between the platform and structure, cooperating means upon the platform and structure for holding the platform against tilting movement and in load supporting position, and means carried by said structure for engagement with the tripping element to impart an abrupt rearward and downward movement to the platform relative to said structure.

3. In mail delivery apparatus the combination with a car and a tripping element adjacent the path thereof, of a structure 65 hingedly connected to the car and mounted to swing laterally rearwardly relative thereto to position the structure at right angles to the side of the car, a supplemental frame hingedly mounted in said structure, a tiltable platform carried by the supplemental frame, cooperating means upon the platform and structure for holding the platform in load supporting position, an arm depending from the structure for actuation by the tripping element, and means operated by said 70 arm for shifting the supplemental frame and successively releasing the platform and imparting an abrupt rearward and downward swinging movement thereto.

In testimony that I claim the foregoing as my own, I have hereto affixed my signature in the presence of two witnesses.

JOHN A. CHAMBERS.
